UNITED STATES PATENT OFFICE.

HORACE S. FAIRBANKS, OF RACINE, WISCONSIN.

WAGON-BODY CORNER.

SPECIFICATION forming part of Letters Patent No. 410,508, dated September 3, 1889.

Application filed May 29, 1889. Serial No. 312,651. (No model.)

To all whom it may concern:

Be it known that I, HORACE S. FAIRBANKS, a citizen of the United States, and a resident of Racine, in the county of Racine and State of Wisconsin, have invented certain new and useful Improvements in Wagon-Body Corners; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a perspective view. Fig. 2 is a vertical section. Fig. 3 is a top view of the corner. Fig. 4 is a detail, and Fig. 5 is a horizontal section of the corner.

This invention relates to certain improvements in corner iron or joints for wagon bodies and boxes; and it consists of the novel construction and combination of parts, as will fully appear from the following description and accompanying illustrations.

25 In carrying out my invention I make use of a casting or metallic corner-piece A, of which four are applied to a vehicle-body, one at each corner. This corner-piece or casting is rounded or convex upon the outside and 30 has its vertical side edges presented to and abutting against the ends of the panels a of the body A'. The casting or corner-piece A has bolted or firmly secured to its inner side a vertical cleat or bar b, which is beveled or 35 chamfered to fit in the corner between connecting-panels. The casting or corner-piece A may be concave or curved upon the inner side, or it may be straight or plain, it, however, always being round or convex on the outside.

40 Upon the upper edges of the panels may be applied or fastened re-enforcing-plates c c, adjacent to and abutting against the castings or corner-pieces. The side edges of the casting A, when its inner side constitutes the chord 45 of an arc, stand at an acute angle to the side edges of the cleat b. When the inner surface of the casting is curved or concave or less than a complete chord of the arc, its side edges stand at right angles to the side edges of the 50 cleat or post. Consequently the side edges of

the panels will be accordingly square or beveled.

The cleat b is secured to the bottom frame of the body by a stout iron bracket d, bolted to the said cleat and at its lower end to said frame. The upper end of the bracket d has an eye d', and with this eye engages the beak of a lever hook or latch e, whose fulcrum is a pivot-bolt e', passing through a plate f and the upper framing, and also through the panel of 60 one side of the body. This plate f is bolted or screwed to said framing and prevents the marring or mutilation of the wooden parts, which would otherwise be exposed to the action of the lever hook or latch as it is manipulated. The plate f is an extension or offset of the upper end of an iron post g, the lower end of which rests upon the bottom frame of 65 the body, and has also an offset or plate g' upon the side opposite to that having the upper offset or plate f. This offset or plate g' is bolted to the end-gate a' and received in a 70 recess or gain in the side edge of the bottom frame, while its extreme lower end has an eye h, which engages a pintle h', whose shank or 75 plate portion is screwed or fastened to the under side of the bottom frame. The end-gate, it will be seen, is thus furnished with hook-and-hinge connection to the bottom and top framing.

Having thus described this invention, what I claim, and desire to secure by Letters Patent, is—

1. The wagon body or box and corner iron or piece having a rounded or convex outer surface and connected to a cleat or post adapted to be fitted at the corner-joint of the body or box, substantially as set forth.

2. The corner piece or iron having a rounded or convex outer surface and an inner curved or concave surface and its securing-cleat, substantially as set forth.

3. The corner piece or iron having an outer rounded or convex surface and an inner concave surface and the post or cleat having one 95 side edge beveled or chamfered and the opposite side edge rabbeted, substantially as set forth.

4. The combination, with the corner-piece, the end-gate, and panel of the vehicle-body, 100

of the bracket secured to the cleat of the said corner-piece and having at each end an offset or plate, one plate or offset entering a recess or gain in the edge of the bottom frame and 5 having a hinge-connection with said frame, the offset or plate at the other end of the bracket having a hook-and-eye connection with the end-gate, substantially as set forth.

5. The combination of the corner piece or 10 iron having an outer rounded or convex surface, the post or cleat having one side edge

beveled and the opposite side edge rabbeted, and the square or bevel ended panels fitting the cleat or post, one of said panels entering the rabbet of said post or cleat and the corner 15 iron or piece, substantially as set forth.

In testimony whereof I affix my signature in presence of two witnesses.

H. S. FAIRBANKS.
